UNITED STATES PATENT OFFICE.

JOSEPH ZOLOTAR, OF DETROIT, MICHIGAN.

BANK AND CAR PROTECTIVE DEVICE.

Application filed January 12, 1925. Serial No. 1,753.

To all whom it may concern:

Be it known that I, JOSEPH ZOLOTAR, a citizen of Russia, residing at Detroit, in the county of Wayne and State of Michigan, have invented certain new and useful Improvements in Bank and Car Protective Devices, of which the following is a specification, reference being had therein to the accompanying drawings.

10 This invention relates to means for facilitating the armed protection of persons, property and valuables in buildings or enclosures such as banks, stores, mail or express cars, whereby provision is made for the armed 15 resistance of an attack; and the object of this invention is to ensure adequate protection for the marksman or person offering such armed resistance whereby he may be permitted to fire on intruders from a point 20 of vantage without exposing himself materially to the return fire of such intruders should that take place.

The invention further aims to provide a 25 movable protective enclosure for such marksman whereby he may establish or approach a point of vantage in different parts of the room in which he is operating according to the nature and direction of the attack, an incidental object being to provide, in a room, 30 a track and a protective enclosure movable on the said track, such enclosure being adapted to permit the entry thereinto of a marksman and to be effectually closed for the protection of the said marksman after 35 he has made such entry.

A still further object is to provide a protective device arranged in combination with an ante-room or enclosure wherein a marksman is primarily situated in a position more 40 or less inaccessible to intruders whereby the said marksman may enter the said protective device in the seclusion of said ante-chamber free from molestation and, after closing the said device upon himself, may 45 then effect its propulsion or be moved therewithin to the point of vantage from which he is to operate.

Still further objects subsidiary to or resulting from the aforesaid objects, or from 50 the construction or operation of the invention as it may be carried into effect, will become apparent as the said invention is hereinafter further disclosed.

In carrying the said invention into effect, 55 I provide a room which may be a banking chamber, a store, a railroad car or other en-

closure requiring protection, with a bullet proof casing mounted upon suitable supporting means such as by being suspended from a rail in such manner that the said casing may be moved from one location to another as may be desired, the said casing having a door which may be opened to permit entry into the casing of a marksman and to close for his protection after such entry and also provided with restricted firing openings through which the said marksman may shoot at intruders within his range.

In the case of banks and similar places the rail may extend from an ante-room to the 70 cashier's counter or wicket and the casing when not in use form the closure for an opening in the wall of said ante-room whereby the door of the said casing opens into the said ante-room and permits a marksman to pass from the ante-room to the casing without exposing himself to fire or missiles thrown by intruders approximate to the 75 said cashier's wicket, the said casing after the entry of the marksman thereinto being capable of propulsion along the supporting rail to the cashier's wicket from which point the marksman may give battle to intruders without exposing himself to danger. If desired the means of propulsion of the casing 80 may be in the form of manually operated means within or extending into the casing so that the movement of the casing may be effected from within the said casing by the 85 marksman.

All of which is more particularly described and ascertained hereinafter, by way of example, having reference to the accompanying drawings, wherein—

Figure 1 is a broken perspective view of 95 the interior of a bank illustrating an embodiment of the said invention therein;

Figure 2 is a diagrammatic plan of the same;

Figure 3 is a fragmentary sectional view 100 illustrating the method of suspending and operating a casing from the rail;

Figure 4 is an elevation of a mail car partly broken away to indicate the arrangement of a protective casing therewithin according to the said invention;

Figure 5 is a sectional plan of the same;

Figure 6 is a transverse section of the same, taken on the line 6*-6*, Figure 5; and

Figure 7 is a detail perspective view of the 110 casing including part of the supporting rail.

Similar characters of reference indicate

similar parts in the several figures of the drawings.

Referring first of all to Figures 1, 2 and 3, the building 1 is shown as enclosing a cashier's room 2, provided with a wicket 3, and behind this room is a further ante-room 4, the structural arrangement of which rooms does not enter into the present invention.

- 10 It will be noted, however, that the ante-room is provided with an opening 5 communicating with the cashier's room 2 and that from the upper part of this opening to the upper part of the cashier's wicket a rail 6 extends, this rail forming a support for a casing 7 which is suspended therefrom by arms 8, the upper ends of which are provided with rollers 9 travelling along the said rail 6.
- 15 20 The said casing is also provided with a door 10 and is intended when in its rearmost position on the supporting rail to act as a closure for the opening 5 as indicated in dotted lines in Figure 1, and in full lines in Figure 2, in which position the door of the casing opens into the said ante-room 4.

In this arrangement it is intended that the ante-room be occupied by a marksman who may be employed in any capacity with 30 in the ante-room but ready at all times to enter through the door 10 into the casing 7 when it is acting as a closure for the opening 5 between the rooms 4 and 2 so that, upon any predetermined alarm being given 35 by the cashier or others indicating that assistance is needed, the said marksman may enter the casing without exposing himself to the assault of intruders, and close the door of the casing behind him, after which 40 the casing may be propelled to the forward end of the room 2 as indicated in full lines in Figure 1 and in dotted lines in Figure 2. From this position the marksman may 45 open fire upon the intruders without danger to himself, and his progress to this point of vantage cannot be impeded by the said intruders opening fire upon him, due to the complete protection which the casing affords.

50 Obviously, many methods of effecting propulsion of the casing along the rail offer themselves, and for the sake of illustration a simple cable 11 is shown, the forward end of which is fastened to a bracket 12 at the 55 forward end of the supporting rail, the said cable passing over a pulley 13 on the upper end of the casing and through an opening 14 therein, whereby the marksman may effect the movement of the casing from the 60 opening 5 to the wicket simply by pulling upon the said cable and drawing it into the casing.

In Figures 4, 5 and 6 the application of the device to a mail car 15 is clearly shown.

65 Usually these cars are provided with doors

16 and 17 on opposite sides of the car, either of which may be opened, and either of which may be attacked when robbery of the car is attempted. In this case I prefer to arrange a supporting rail 18 diagonally 70 across the car between the said doors 16 and 17 so that by moving the casing 7 to one or other end of the said rail it will be conveniently situated with respect to one or other of the doors according to requirements. 75

In this case the provision of an ante-room is usually unnecessary due to the different form of attack usually adopted where mail cars are concerned, ample opportunity usually being given to enter and close the casing. 80 Also the propulsion of the casing by the marksman may not be considered necessary and means therefor may be omitted as in the illustrations, Figures 4, 5, 6 and 7.

Herein and in the claims, the term "room" 85 is used in a general sense as it may include structures such as cars or pay stations or other enclosed areas requiring protection.

This invention may be developed within the scope of the following claims without 90 departing from the essential features of the said invention, and it is desired that the specification and drawings be read as merely illustrative and not in a limiting sense, except as necessitated by the prior art. 95

What I claim is:—

1. In combination with an enclosure having openings on opposite sides thereof, protective means against intruders, comprising a casing adapted for the enclosing of a marksman, said casing having restricted firing openings therein, and means extending between said openings movably supporting said casing whereby its location may be affected at one or other of said openings. 100

2. In combination with an enclosure having openings on opposite sides thereof, protective means against intruders, comprising a casing adapted for the enclosing of a marksman, said casing having restricted firing openings therein, and an overhead rail 110 extending between said openings, said casing being movably supported by said rail in a raised position. 115

3. The combination with a room, of an ante-chamber opening thereunto, protective means against intruders comprising a casing normally closing the opening between said room and said ante-chamber, said casing having restricted firing openings therein, and means movably supporting and guiding said casing whereby it may be moved across the room from said opening. 120

4. The combination according to claim 3, wherein the room is provided with a wicket and said supporting means are extended from the opening of said ante-room in the direction of said wicket. 125

5. In an enclosure having openings on 130

opposite sides thereof, an overhead track extending diagonally from one side of one of said openings to the opposite side of the other of said openings, and means for the protective enclosing of a marksman comprising a ported casing movably suspended from said track.

In testimony whereof I affix my signature in the presence of two witnesses.
